ROCKING CHAIR

Vincent E. Gardner, Wayne, Mich., assignor to Marilyn
Sue Powers, Allen Park, Mich.

Filed Apr. 12, 1967, Ser. No. 6,652

Term of patent 14 years

(Cl. D15—6)

FIGURE 1 is a perspective view of a rocking chair showing the new design.

FIGURE 2 is a side elevation view of the new design.

FIGURE 3 is a front elevation view of the new design.

FIGURE 4 is a back elevation view of the new design.

The side of the chair not shown in FIGURE 2 is a mirror image of the side shown.

I claim:

The ornamental design for a rocking chair, substantially as shown and described.
